Primary Examiner — Ian Simmons*Assistant Examiner* — Khawaja Anwar(74) *Attorney, Agent, or Firm* — Cantor Colburn LLP(57) **CLAIM**

The ornamental design for a door for refrigerator, as shown and described.

DESCRIPTION

FIG. 1 is a perspective view of a door for refrigerator, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is an enlarged partial perspective view thereof;

FIG. 9 is an enlarged partial front view thereof;

FIG. 10 is an enlarged partial rear view thereof;

FIG. 11 is an enlarged partial side view thereof;

FIG. 12 is another enlarged partial side view thereof;

FIG. 13 is an enlarged partial top view thereof;

FIG. 14 is an enlarged partial bottom view thereof; and,

(Continued)

FIG. 15 is an enlarged view of the encircled portion 15, as shown in 8.

The broken lines illustrating portions of the door for refrigerator form no part of the claimed design.

The dot-dash broken lines encircling enlargement portions of the design form no part of the claimed design.
